UNITED STATES PATENT OFFICE.

HERMAN C. BINKELE, OF TIGARD, OREGON.

ELEVATOR CLOTHES DRIER.

Application filed July 20, 1926. Serial No. 123,743.

This invention relates to improvements in clothes drying apparatus.

The primary object of this invention is the provision of an improved clothes drying apparatus similar to that set forth in my co-pending application, Serial No. 78,891, filed January 2, 1926, but embodying an improved supporting and operating arrangement by means of which to provide for the facile operation of a clothes carrier for a maximum vertical movement along a vertical supporting device without impedance by supporting brackets and other operating details.

A further object of this invention is the provision of an improved clothes drier embodying a slideable carriage mounted in a novel manner to a vertical stationary support.

A further object of this invention is the provision of novel means to automatically catch a movable clothes supporting carriage at the top of its movement with respect to a stationary support.

A further object of this invention is the provision of an improved type of clothes drier adapted for support in a novel relation within a compartment provided within the hollow of a wall construction, or in a casing compartment.

Other objects and advantages of this invention will be apparent during the course of the following detailed description.

In the accompanying drawings, forming a part of this specification, and wherein similar reference characters designate corresponding parts throughout the several views,

Figure 1 is a fragmentary side elevation, partly in section, showing the improved clothes drier supported in an elevated relation with respect to a stationary supporting rail or member, and showing the cooperating details of the clothes drier.

Figure 2 is a sectional view taken substantially on the line 2—2 of Figure 1, showing the improved type of stationary vertical support and operating means for moving the carriage therealong.

Figure 3 is a front elevation of a movable carriage of a clothes drier and its automatic catch or detent.

Figure 4 is a top plan view of the improved clothes drier.

Figures 5 and 6 are cross sectional views taken substantially on their respective lines in Figure 1 of the drawings.

Figure 7 is a fragmentary rear elevation, partly in section, of the upper end of the

vertical support for the clothes drier carriage.

Figure 8 is a modified form of invention showing the relation in which the improved clothes drier may be collapsibly mounted within a hollow of a wall or within a wall casing.

Figure 9 is a front elevation, partly in section, showing the clothes drier collapsed within the wall casing with the carriage in an elevated relation therein.

Figures 10 and 11 are views showing the upper and lower ends of the casing in which the collapsible clothes drier is mounted, and showing the construction thereof for effecting the mounting of the clothes drier, Figure 11 being taken substantially on the line 11—11 of Figure 12.

Figure 12 is a front elevation of the lower portion of the wall casing.

Figure 13 is an enlarged fragmentary sectional view taken through a detail of a closure used in connection with the wall casing.

In the drawings, wherein for the purpose of illustration are shown preferred and modified embodiments of the invention, the letter A may generally designate the improved clothes drier adapted to be mounted upon any type of wall or other support B and consisting principally in the provision of a stationary supporting rail or member C and a carriage D movably connected in a novel relation upon the face of the rail C. In the modified form of invention E the supporting rail or member C' is collapsibly mounted in a novel relation within a cabinet G, or within the hollow of a wall F.

The supporting rail or member C for the preferred embodiment A is stationary, but the same is collapsibly mounted in the cabinet or wall type of clothes drier illustrated in Figures 8 to 13 inclusive. In both forms of the invention the rail C comprises a vertical elongated body 15 which may be of wood or metal, and which inwardly of the front face thereof is provided with a central longitudinally extending groove 16 for a purpose which will be subsequently described. At the upper and lower ends of the body 15 at the terminals of the groove 16 transverse openings 18 and 19 are respectively provided, wherein pulleys or grooved wheels 20 and 21 respectively are rotatably mounted upon suitable pins 22, so that the grooves of said wheels 20 and 21 align with each other beyond the rear surface 24 of the

body 15 and also align with the groove 16 on the front face of the body 15 of the rail or supporting member C.

The rail body 15 at the rear longitudinal corners thereof is provided with elongated grooves 30 and 31 which outlet at the sides and on the rear surface of the body 15 and provide track surfaces adapted to receive rollers 33 and 34 respectively of the carriage 10 construction B which will be subsequently mentioned, in order to guide movement of the carriage.

The carriage construction D for each of the forms of the invention preferably includes a 15 rectangular body 35, which may be of wood or metal or other approved material, which is as short in height as permissible, and in any event much shorter than the supporting rail or member C. The body 35 at the opposite 20 sides thereof and adjacent the upper end thereof is provided with substantially L-shaped hooks 36 and 37, best illustrated in Figure 6 of the drawings, having screw threaded shanks embedded at 38 in the material of the body 35, and extending at right 25 angles from the rear surface of the body 35, in spaced slidable relation along opposite longitudinal sides of the supporting rail body 15, and at their rearmost ends having the in- 30 turned aligning spindle ends 40 whereon the rollers 33 and 34 are respectively rotatably mounted for rolling in the guide grooves 30 and 31 above mentioned. This supports the upper end of the carriage body 35 for sliding 35 movement along the rail body 15, and adjacent its lower end the body 35 is provided with a stationary guide stem 45, which is placed at the longitudinal center of the body 35 and extends from the rear surface thereof 40 for sliding engagement in the vertical groove 16 of the supporting rail C, in the relation of parts illustrated in Figure 1 of the drawings.

At its upper end the carriage body 35 is provided with a clothes supporting arrangement K illustrated in Figure 4 of the drawings, including the bracket 48 which is mounted upon the said upper end of the carriage D, said clothes supporting arrangement K being of the type described in detail in my 50 co-pending application, Serial No. 78,891, filed January 2, 1926.

At its lower end and inwardly from the rear surface thereof the body 35 is provided with thumb tacks 49, or analogous elements, 55 providing small heads which project rearwardly from the rear surface of the body 35 for sliding abutment against the front face of the supporting rail body 15 at opposite sides of the groove 16, so that the rear surface 60 of the carriage body 35 cannot of itself slide against the front face of the body 15, and thus lessening the frictional resistance to sliding of the carriage upon the supporting rail C, as can readily be understood from Figure 1 of the drawings.

As to the means for operatively moving the carriage D along the support C a cable 55 is provided, which has one end 56 thereof secured substantially centrally in the carriage body 35 between the roller brackets thereof and the guide pin 45; the cable 55 extending upwardly in the guide groove 16 of the body 15, and being trained over the upper roller 20 and thence extending downwardly along the back surface of the supporting rail body 15 and being trained about and beneath the pulley 21 and at its free lower end said cable 55 having a finger engaging loop 57; said free end of the cable 55 extending downwardly from the front of the supporting rail body 15, so that an operator may grasp the same and by pulling upon it elevate the carriage D upwardly along the supporting rail or member C as can readily be understood; the weight of the carriage D being sufficient 80 to lower the same.

Releasable detent means is provided for automatically holding the carriage D in its uppermost position upon the support rail C when the same is elevated to such position. 90 This means includes detent levers 60 and 61 pivotally supported upon pivot pins 62 at the opposite sides of the carriage body 35; the said pivot pins securing the detent levers intermediate their ends so that the rear ends 95 thereof extend beyond the plane of the rear surface of the body 35 for cooperation with the laterally projecting ends of a pin 65 which is mounted upon the body 15 of the support C and extends laterally from the opposite side edges thereof in the relation of parts illustrated in Figures 1 and 5 of the drawings. These projecting ends of the detent levers 60 and 61 have the upper surfaces 67 thereof beveled for easy sliding of the said bevel edges over the projecting ends of the pin 65 during the upward elevation of the carriage D, so that the detent levers 60 and 61 may be pivoted to permit their rear ends to lift above the retaining pin 65 in a manner which is perfectly obvious. The forward ends of the retaining levers 60 and 61 at the opposite sides of the pivot axis thereof from the beveled edges 67 have the upper ends of divergent wires 70 and 71 connected therewith; the divergent wires 70 and 71 extending downwardly in a converging relation and being twisted together at 72 and extending downwardly along the longitudinal center line of the carriage body 35. Of course the wires 120 70 and 71 may be of other material than wire and the same are preferably rigid, as is also the twisted portion 72 which terminates at its lower end in an eye 73. A screw eye 74 is preferably detachably connected in the lower end of the carriage body 35, and the twisted portion 72 extends downwardly in a loose relation through the eye 74, so that the eye 73 thereof is positioned at a location below the screw eye 74. An operating cable 75, 125

preferably flexible in nature is mounted and connected at 76 in the eye 73 and extends upwardly in a threaded relation through the screw eye 74 and is looped thereover and extends downwardly in a depending relation along the front of the support rail C, and at its lower end terminates in a finger engaging loop 78.

In the preferred form of invention A the 10 supporting rail C is mounted stationary upon the wall B. This is effected by means of upper and lower substantially L-shaped brackets 80 and 81, which have leg portions 82 for overlying the upper and lower edges of 15 the supporting rail C, the same being secured thereto by screws 83, and said brackets also including right angled leg portions 85 in a plane spaced from the rear surface of the supporting rail body 15 for attachment by 20 screws 86 to the wall B, so that the rear surface of the supporting rail is spaced from the surface of the wall B to permit the unobstructed operation of the cable 55 and the pulleys over which the same is trained.

25 It is apparent that, for the form of invention A, the carriage D may slide substantially the entire length of the supporting rail or member C and especially at the upper end of the rail C there are no obstructing brackets 30 or extensions to impede the uppermost elevations of the carriage D. The carriage D, as is perfectly obvious, is elevated by means of the cable 55 to a desired position, although it is practically always elevated to the extreme position at the upper end of the supporting rail body 15 where the same is retained by the detents 60 and 61.

To limit the downward movement of the carriage D upon the supporting rail C it is 40 preferred to provide stop pins 86 and 87 at opposite sides upon the rail body 15, which receive the projecting ends of the retaining pawls or detents 60 and 61 in engagement therewith to limit the lowered movement of 45 the carriage as illustrated in dot and dash lines in Figure 1 of the drawings, so that the carriage is in position to be loaded with clothes. This loading location is at a convenient height, and by means of the cable 55 50 the carriage may then be elevated to the ceiling of the room in which the clothes drier construction is placed.

The release of the pawls or detents 60 and 61 is perfectly obvious. Merely by pulling 55 upon the cord 75 the rigid twisted portion 72 and the portions 70 and 71 of the wire arrangement connected with the pawls are elevated, to swing the forwardly extending ends of the pawls or detents 60 and 61 upwardly 60 and pivot them upon their pivot pins 62, and this swings the rearwardly projecting ends of said detents out of the path of the pin extensions 65, so that the carriage may drop as permitted by the operator. Of 65 course, pins 90 are carried by the carriage D,

at opposite sides thereof, which limit the downward movement of the forward ends of the detent levers 60 and 61 to a horizontal position, so that said forwardly extending ends of said levers may only swing upwardly 70 to release the carriage for a lowered movement.

Referring to the wall or cabinet type of supported clothes drier, it is preferred to provide a cabinet or casing G consisting of a 75 rear wall 100, side walls 101 and 102; top wall 103; and bottom wall 104, thus defining a compartment 105 in which the supporting rail C' with its above described carriage D' is collapsibly and movably mounted.

80 As to the lower end mounting of the supporting rail C' in the cabinet G, a substantially V-shaped supporting rod 107 is provided, having the remote ends 108 thereof pivoted in the walls 101 and 102 adjacent 85 the rear wall 100. The apex portion 109 of the V-shaped rod 107 is pivoted in the lower end of the supporting rail body 15', as illustrated in Figures 8 and 9 of the drawings, so that upon rear swinging of the rod 107 the 90 body 15' will be moved into the compartment 105 against the rear wall 101, but upon forward movement of the rod or supporting member 107 the supporting rail body 15' may be swung forwardly into the front of the 95 compartment 105 as illustrated in the dotted lines in Figure 8 of the drawings.

99 As to the upper end mounting of the supporting body 15', the same is preferably provided with a transverse rod 111 which extends considerably beyond the sides of the rail body 15', in fact, being greater in width than the compartment 105, so that the opposite ends thereof are slidably mounted in inclined grooves 112 provided inwardly of the 105 inner surfaces of each of the side walls 101 and 102 of the cabinet G. It can thus be readily understood that the upper ends of the supporting rail construction C' will be guided into or from the compartment 105 with the 110 pivotal movement of the lower end thereof upon the supporting rod 107.

The operation of the supporting rail construction C' and carriage construction D' for the form of invention E is exactly as above described for the form of invention A.

A novel type of closure construction is provided for the cabinet G which consists in the provision of a flexible cover 115, of sheet material, which at the opposite sides thereof 120 slides within suitable grooves 116 provided inwardly of the side walls 101 and 102. The closure sheet 115 slides vertically and it collapses into inclined grooves 118 provided in the extension walls 119 below the bottom wall 105 of the cabinet, as illustrated in Figure 8 of the drawings, so that the closure 115, in fact, collapses behind a front stationary wall 120, which may be a part of the wall construction of the room in which the clothes drying 130

device is mounted. The upper end of the closure sheet 115 is provided with a retaining rail 121, which facilitates the operation thereof and engages a lower retaining piece 122 formed with the framework in which the cabinet is mounted in the wall. It is also preferred to provide a hand engaging slot 125 in the closure sheet 115 to facilitate the closing movement. The closure may be held closed by frictional engagement in its grooves or suitable retaining latches may be provided therefor.

It is of course understood that the cabinet G may be placed upon the outer surface of a wall or the wall may be hollowed to accommodate the same in a "built in" relation.

From the foregoing description of this invention it is apparent that novel types of clothes driers have been provided which are 20 efficiently constructed for facile operation and being especially compact for a desirable mounting in a room wherein space is a vital consideration; the improved clothes driers being provided for use in an environment 25 such as set forth in my co-pending application above referred to.

Various changes in the shape, size, and arrangement of parts may be made to the forms of invention herein shown and described, 30 without departing from the spirit of the same or the scope of the claims.

I claim:

1. In a clothes drier construction the combination of an elongated vertically disposed 35 supporting rail, a slideable carriage having a vertical reciprocating movement on the rail, a pawl lever pivoted between its ends on the carriage, retaining means on the supporting rail for engagement by the pawl at an end 40 thereof, retaining means on the carriage to limit the movement of the pawl in a predetermined direction to permit said pawl to engage said first mentioned retaining means and hold the carriage at the upper end of its 45 movement upon said supporting rail, a rigid member pivotally connected with the pawl and extending downwardly along the carriage, a screw eye on the carriage receiving end of said rigid member remote from its 50 pivot connection, a flexible cable connected with the lower end of said rigid member below the screw eye and extending upwardly through the screw eye in a threaded relation and depending downwardly along said supporting rail, and means on the carriage for 55 supporting clothes.

2. In a clothes drier construction a clothes supporting carriage having clothes supporting means thereon, levers pivoted at opposite 60 sides of the clothes supporting carriage, a rigid wire pivoted on an end of each of the said levers at locations thereon spaced with respect to the pivots of said levers, said rigid wires converging downwardly and being 65 twisted in a rigid stem, and a screw eye

through which the lower end of the rigid stem extends.

3. In a clothes drier construction of the class described a cabinet providing a compartment therein, a vertical supporting rail, 70 means pivotally mounting the lower end of the supporting rail in the compartment so that the supporting rail at its lower end may be swung back into the compartment or extended forwardly in the compartment, said 75 cabinet in the upper end of the compartment having its opposite sides provided with downwardly inclined grooves, a rod carried by the upper end of the supporting rail slidably engaging in said grooves, a carriage, means so slidably mounting the carriage on said supporting rail for upward and downward movements thereon, and clothes supporting means on the carriage.

4. In a clothes drier construction the combination of an elongated vertically disposed 85 supporting rail, a slideable clothes supporting carriage for the supporting rail, means slidably connecting the carriage on the supporting rail, a pawl lever pivoted between its ends 90 on the carriage, a retaining member on the carriage forwardly of the pivot axis of the pawl lever to limit the downward swinging of the forward end of the pawl lever, but permitting upper swinging of the forward 95 end of the pawl lever, said pawl lever having a rearwardly extending pawl end, means on the support which the said rear end of the pawl lever may engage to support the carriage in a predetermined position on the support when the pawl lever at its forward end 100 engages the retaining means on the carriage, and means carried by the carriage and operatively connected with the forward end of the pawl lever for elevating the said forward 105 end of the pawl lever to release the rear end of the pawl lever from the means on the support which it engages and permit a downward sliding movement of the carriage on the support.

5. In a clothes drier a vertical support, a carriage, spaced bracket arms carried by the carriage between the ends of the latter having 115 slideable guided connection upon said support, said support having a vertical guide groove in the front face thereof, a pin carried by the carriage operable in said guide groove at a location below said bracket arms, bearings on the carriage below said pin in sliding engagement with the front of said support to space the carriage from the support and to relieve the pin from resting engagement with the support while in said groove, and clothes supporting means on the carriage.

6. In a clothes drier construction the combination of a supporting member, a carriage, means slidably mounting the carriage upon the supporting member for vertical sliding movement therealong, a pawl lever pivoted 130

between its ends on the carriage, said pawl lever having the rear upper edge thereof provided with a sloping cam surface, retaining means on the support which the cam surface 5 may engage upon elevation of the carriage to swing the lever downwardly at its rear end and permit the pawl lever to ride past said retaining means, and means cooperating at the opposite end of the pawl lever at the op-

posite side of the pivot thereof from the retaining means of the support to limit the downward movement of the pawl lever at its forward end, so as to permit the rear end of the pawl lever to catch on the retaining means and hold the carriage supported in an elevated relation upon said supporting member. 10 15

HERMAN C. BINKELE.
